The ornamental design for a label sheet with a feed edge assembly, as shown and described.

DESCRIPTION

FIG. 1 is a front view of an first embodiment of a label sheet with a feed edge assembly showing our new design; FIG. 2 is a front view of a second embodiment of a label sheet with a feed edge assembly showing our new design; FIG. 3 is a front view of a third embodiment of a label sheet with a feed edge assembly showing our new design; FIG. 4 is a front view of a fourth embodiment of a label sheet with a feed edge assembly showing our new design; FIG. 5 is a front view of a fifth embodiment of a label sheet with a feed edge assembly showing our new design; FIG. 6 is a front view of a sixth embodiment of a label sheet with a feed edge assembly showing our new design; FIG. 7 is a front view of a seventh embodiment of a label sheet with a feed edge assembly showing our new design; and,

FIG. 8 is a front view of a eighth embodiment of a label sheet with a feed edge assembly showing our new design. The broken line showing of portions of the label sheet with a feed edge assembly is included for the purpose of illustrating environmental structure and forms no part of the claimed design.
